UNITED STATES PATENT OFFICE.

OLUF F. JENSEN, OF COUNCIL BLUFFS, IOWA.

RAILWAY HIGHWAY CROSSING.

Application filed May 23, 1925. Serial No. 32,321.

REISSUED

To all whom it may concern:

Be it known that I, OLUF F. JENSEN, a citizen of the United States, residing at Council Bluffs, in the county of Pottawattamie and State of Iowa, have invented certain new and useful Improvements in a Railway Highway Crossing, of which the following is a specification.

This invention relates to highway crossings over railway tracks, and has for its object to provide slidable and rotatable plates which may be used in connection with the railway ties and track rails, said plates being of such proportion that they may be prepared in stock ready for use and may be conveniently mounted between the track rails to provide a complete, permanent crossing at a less expense of time than ordinary.

The invention broadly includes the use of comparatively thin bearing-plates having flanges or wings projecting downwardly from their longitudinal edges to be disposed between the balls and bases and to be supported on the bases of two adjacent rails, the plates when thus mounted having their wings disposed closely adjacent to the webs of the rails and having their upper surfaces disposed in line with the upper surfaces of the balls of said rails so that vibration usually caused by moving vehicles on crossings may be practically eliminated.

The invention also includes a third rail disposed midway between and approximately parallel with the track rails so that the plates may have a lesser width to permit them to be constructed of thin material, said plates, on account of the construction provided, being adapted to adequately sustain all stresses incident to travel, the third rail having a suitable length and preferably corresponding to the form, in cross-section, of the track rails. Also the invention includes reinforcing ribs for the plates, said ribs being arranged for a support upon the bases of the track rails.

While the invention includes structural parts providing a permanent crossing as a feature of durability, these parts, or so many as is necessary, may be readily removed to permit removal of a broken track rail or for repairs of a rail joint, and the plates provide housings for the rail joints and their usual attachments.

With the foregoing objects in view and others to be mentioned the invention presents a novel and useful construction, com-

bination and arrangement of parts as described herein and claimed and as illustrated in the accompanying drawings, it being understood that changes in form, size, proportion of parts and minor details may be made as found to be of advantage, said changes being within the scope of the invention as claimed.

In the drawing, Fig. 1 is a plan view of a railroad highway crossing showing one embodiment of the invention. Fig. 2 is a sectional detail showing insulation between the plates, for use in connection with a block signal system. Figs. 3 and 4 are details relating to Fig. 5. Fig. 3 is a side view of a bearing-plate showing a groove for receiving the flange of a car wheel. Fig. 4 is a view showing the opposite side of said plate. Fig. 5 is a sectional view on line 5-5 of Fig. 1. Fig. 6 is a sectional view on line 6-6 of Fig. 1. Fig. 7 is a longitudinal section on line 7-7 of Fig. 1, and Fig. 8 is a sectional view on line 8-8 of Fig. 1. Fig. 9 is a sectional view showing a modified arrangement for connecting the plates.

Referring now to the drawing for a more particular description, the invention is shown and described in connection with the railway ties 10 and the parallel track rails A and B thereon, the ball of each track rail being indicated at 11, its base being indicated at 12 and its web being indicated at 13.

For purposes of the invention I provide a third rail C adapted to be disposed approximately parallel with and midway between the track rails A and B. Numerals 14 and 15 indicate bearing-plates disposed between the rail C and track rail A, each plate having wings or flanges 16 projecting downwardly from its longitudinal edges and having its lower side provided with ribs 17, each rib being disposed transversely of a plate. While I have shown only two of these plates, any desired number may be employed, depending upon the width of a crossing, and said plates may have sliding movements on the bases of the rails A and C when building a crossing or when it might be necessary to remove a broken track rail; and blocks 18 may be secured to the rail at the ends of the plates to prevent creeping. These plates are provided with grooves 19 for receiving the flanges of car wheels.

I provide additional rails D and E, these

being disposed outwardly of and approximately parallel with the respective rails A and B. While said rails D and E are shown to be similar to ordinary track rails, this feature is not important, and inverted T-rails may be used for this purpose if desired.

Numerals 20 and 21 indicate bearing-plates adapted to have sliding movements for their mounting between rails A and D shown best in Fig. 5 of the drawings, their wings 22 being supported on the bases of said rails, said plates being provided, transversely, with reinforcing-ribs 23 similar to those described.

Numerals 24, 25 and 26 indicate bearing-plates disposed between the rails B and C, and they are provided at their longitudinal edges with wings 16 and ribs 17 for a support on the bases of said rails B and C, the same as described.

Numerals 27, 28 and 29 indicate bearing-plates disposed between the rails B and E, each being provided with wings 16 and ribs 17 engaging the bases 12 of said rails.

As indicated at e, the ends of the plates at the respective sides of the crossing are inclined downwardly, this being the preferred construction to provide closures, and being of advantage to avoid injury which might occur from loose parts occasionally carried by moving trains, and to prevent accumulations beneath the crossing of sand, dust or snow.

It will be appreciated that the movable feature for the plates operates to advantage since it might be necessary to remove a damaged rail or to repair a rail joint, the fish-plates for the latter being indicated at 30.

The plates 20 and 21 may have outward sliding movements for their removal after the blocks 18 have been detached from the rail A. Also, after detaching the blocks 18 the plates 14, 15, 24, 26, 27 and 29 may be removed by causing them to slide outwardly.

The plates 25 and 28, which cover the rail joint, may have rocking movements to effect their removal, it only being necessary to move the plates 24, 26, 27 and 29 a limited distance.

In order that sand, dust or other similar substances will not move downwardly between the ends of the plates, suitable flanges f and recesses g are provided for their abutting ends, said flanges being adapted to engage in the recesses when the parts are assembled as a complete crossing. Also other co-operating fastening devices are provided, as, for instance, projections h adapted to enter apertures k which are provided for the abutting ends of the plates. While, as shown in the drawing, these last named fastening devices are provided for the ribs of two adjacent plates, they may be provided

for other parts of the plates; also the projections h may be of any suitable proportions, the recesses having such proportions that they will receive said projections, the object in view being to prevent undue vibration of the plates when subjected to stresses directed thereto.

The crossing as described may have any required width, and while it is shown as a crossing for a single track it, of course, may have a length sufficient to cross any required number of tracks. Numerals 31 indicate approaches to the crossing which may be constructed of any suitable material.

In Fig. 2 a pair of horizontal beams 32 are shown as a substitute for the rail C, and between these beams is disposed an insulating plate 33 adapted for use in instances where a railway is operating under a block-signal system, it being assumed that the plates 15' and 25' are of metallic construction and therefore would operate as electrical conductors between the rails A and B.

While the rail C is of advantage in the construction of the herein described crossing, it could be dispensed with if plates of considerable thickness were used, and therefore I do not wish to be limited to the use of said rail.

Fig. 9 illustrates a modified form of the invention since the wings 16 of the bearing-plate 25 are provided at one of their ends with recesses g and k, the wings at its opposite end being provided with projections f and h. This construction is clearly within the scope of the invention and it permits the projections f and h of the bearing-plate 24 to enter recesses g and k of the bearing-plate 26 after the plate 25 has been removed, this feature being an advantage in manufacturing or production to permit interchange of the plates.

While I have shown and described a rail C between two track rails and identified it as a "third rail," it is obvious that the scope of the invention permits more than a single rail C to be employed, and I do not wish to limit myself to the employment of a single rail C.

I claim as my invention,—

1. A highway crossing for the rails of railway tracks comprising bearing-plates disposed end to end between said rails in engagement with the bases and with their upper surfaces approximately in alignment with the upper surfaces of said rails, said bearing-plates being provided with terminal recesses and projections and adapted to have sliding movements on said bases, the terminal projections of one bearing-plate entering the terminal recesses of an adjacent bearing-plate.

2. In a highway crossing for the pair of rails of a railway track, a third rail having a form in cross-section corresponding to

- and adapted to be disposed between the rails of said track, and bearing-plates each having wings projecting downwardly from its longitudinal edges for engaging the base of 5 a track rail and the base of the third rail.
3. In a highway crossing for the pair of rails of a railway track, a third rail having a base and adapted to be disposed between the rails of said track, a plurality of bearing- 10 plates each having downwardly projecting wings and adapted to have sliding movements on the base of a track rail and base of the third rail, and means to prevent sliding movements of the bearing plates.
- 15 4. In a highway crossing for the pair of rails of a railway track, a third rail having a form in cross section corresponding approximately to and adapted to be disposed midway between the rails of said track, bearing-plates each having downwardly 20 projecting wings at its longitudinal edges and having ribs disposed transversely of and connected with its wings, said plates being adapted to be disposed between with 25 their wings seated on the bases of the third rail and rails of said track.
5. In a highway crossing for the pair of rails of a railway track, a third rail having a form in cross-section corresponding approximately to and adapted to be disposed 30 between the rails of said track, bearing-plates adapted to be slidably disposed on the bases with their upper surfaces in line with the upper surfaces of the third rail and rails
- of the track, and means to prevent sliding 35 movements of the bearing-plates relative to the rails of said track.
6. In a highway crossing for the pair of rails of a railway track, a third rail having a base and adapted to be disposed between the rails of said track, bearing-plates each disposed between and mounted to permit sliding movements on the bases of the third rail and track rails to permit removal of 40 said plates from the crossing, and bearing-plates normally seated on the bases of the third rail and track rails, each adapted to have a swinging movement transversely of the rails to permit removal of said plates 45 from said crossing.
- 50 7. In a highway crossing for the rails of a railway track, a third rail having a base and disposed between the track rails, bearing-plates disposed end to end between the third rail and track rails in engagement 55 with the bases and with their upper surfaces in alignment with the upper surfaces of the track rails and third rail, said bearing-plates being provided with terminal recesses and projections and adapted to have sliding movements on said bases, the terminal projection of one bearing-plate entering the terminal recess of an adjacent bearing-plate.
- 60 In testimony whereof, I have affixed my 65 signature.

OLUF F. JENSEN.
